GARMENT HEM MARKER

Felix De Bucci, Providence, R. I.

Application July 21, 1934, Serial No. 736,416

2 Claims. (Cl. 33—9)

This invention relates to skirt and hem markers, and has for its principal object the production of a simple and efficient means for facilitating the marking of the length of a skirt or other garment.

A further object of this invention is the provision of a simple and efficient garment marker consisting of a pair of substantially parallel blades, the edges of which are angularly bent, the edges of one blade being adapted to fit in nested relation with respect to the edges of the adjoining blade for the purpose of clamping between the blades a portion of the garment, whereby the garment will be folded slightly in an outward direction to provide a bead-like extension adjacent the edges of the blades so that the garment may be easily marked by means of a pin, a basting thread, or through the medium of a chalk line at any desired point.

A still further object of this invention is the production of a simple and efficient marker, the base of which consists of a pair of pivotally connected members which may be moved at right angles to each other for supporting the marker while being used, and the members may be swung one upon the other for the purpose of packing.

With these and other objects in view this invention consists in certain novel combinations, and arrangements of parts as will be hereinafter more fully described and claimed.

In the drawing:

Figure 1 is a front elevation of the marker;

Figure 2 is a perspective view of the marker showing the device in operation;

Figure 3 is a vertical sectional view taken on line 3—3 of Figure 1;

Figure 4 is a transverse sectional view taken on line 4—4 of Figure 3;

Figure 5 is an edge elevation of the bottom portion of the marker showing the manner in which the base members may be swung one upon the other to accommodate a minimum amount of space in packing;

Figure 6 is an enlarged fragmentary sectional perspective view through the two measuring blades of the marker showing the manner in which the material may be gripped between the blades of the marker while being measured;

Figure 7 is an enlarged transverse sectional view taken on line 7—7 of Figure 1.

By referring to the drawing, it will be seen that the marker consists of a base A, which base A comprises base members 10 and 11, the members 10 and 11 being pivotally connected by means of a suitable journal pin 12. The members

10 and 11 are provided with depending feet 13 and 14, respectively. The base member 10 is provided with an upwardly extending lug 15 upon its upper face, as shown in Figure 3.

Fixedly secured to the opposite faces of the lug 15 are arranged the substantially parallel measuring blades 16, which measuring blades 16 are adapted to extend vertically upon the base and are provided upon their outer faces with suitable graduations 17. The blades 16 are normally held in spaced relation through the medium of the lug 15 as is shown in Figure 3, to allow the material which is being measured to easily slide between the blades when desired. These blades 16 are preferably formed of spring sheet metal and each blade is provided along its longitudinal marginal side edges with oppositely bent angularly extending longitudinal flanges 18, the flanges 18 extending at a radical angle to the transverse axis of the blades 16. The flange 18 upon one side edge of each blade is inclined forwardly whereas the flange upon the opposite side of the blade is inclined rearwardly at an angle. The flanges 18 of the two measuring blades are bent at a uniform angle so as to permit the blades 16 to snugly fit in nested relation when pressed together to a position, such as is shown in Figures 6 and 7 in detail. Each flange 18 is provided with a series of substantially V-shaped notches 19 along the periphery thereof, the notches 19 being equally spaced and coinciding with the graduations 17.

By referring in detail to Figures 6 and 7 it will be noted that the flanges 18 by being bent at a radical angle to the transverse axis of the blade 16 will cause a piece of material 20 placed between the blades 16 to be extended or bent outwardly, as indicated at 21 in Figures 6 and 7 along the marginal outer edges of the flanges 18. This will provide a longitudinal bead-like rib or fold 20 of the material 20 along the edge of the flanges 18 and will facilitate the placing of a pin 22, or other suitable marking such as a chalk line, or basting thread, through the material 20 at the point 21 and at a point registering with one of the notches 19. The manner in which the material 20 is extended or folded outwardly, as indicated at 21, will permit a person to easily insert a pin or needle through the fold 20 and one of the notches 19 by using only one hand while the other hand may be used for holding the blades 16 closely together in a clamping position, such as is shown in Figures 6 and 7. The material is in this way held in an outwardly extended position and the marking of the material will thereby be greatly

facilitated from point to point in a minimum amount of time and with a minimum amount of effort in order to provide a maximum amount of accuracy. Ordinarily, in markers of this general character, it is necessary that the operator employ two hands for picking up the cloth in order that a proper marking may be obtained. As soon as the marking has been made, the blades may be released by the fingers of the operator and the material to be marked may be easily removed from between the blades when the marker may then be moved if desired to another position, or the person to whom the material is being fitted may move or turn and the material will also move or turn in order that the proper marking may continue until it is entirely completed.

When the device is not in use, the base member 11 may be swung to the position shown in Figure 5 under the base member 10, and in the direction shown by the arrow in Figure 4 to cause the base A to be accommodated in a minimum amount of space.

It should be understood that certain detail changes in the mechanical construction, combination, and arrangement of parts may be em-

ployed without departing from the spirit of the invention so long as such changes fall within the scope of the appended claims.

Having described the invention, what is claimed as new is:—

1. As a new article of manufacture, a marker comprising a base, a pair of vertically extending spaced spring blades arranged in close relation, each blade having along its longitudinal side edges oppositely bent inclined marginal flanges, the 10 blades being adapted to receive the material to be marked and cause such material to be outwardly extended in a forward direction beyond the edges of the flanges whereby a suitable marking may be placed upon the material. 15

2. A marker of the class described comprising a base consisting of a pair of pivotally secured members, one member being adapted to swing relative to the other and interfit in nested relation, and one member being movable from a 20 horizontal registering position to a position at right angles to the other member, and measuring blades carried by said base.

FELIX DE BUCCI.
